(57)

CLAIM

The ornamental design for a sports training bag, as shown and described.

DESCRIPTIONFIG. 1 is a perspective view of sports training bag; FIG. 2 is a front view of the sports training bag depicted in FIG. 1 with the back view being identical to FIG. 2; and, FIG. 3 is a top view of the sports training bag depicted in FIG. 1, where the bottom view is identical to FIG. 3 except for lacking the strap shown in ghost.
The broken line showing portions of the sports training bag forms no part of the claim.**1 Claim, 3 Drawing Sheets**# US D1,071,022 S
